UNITED STATES PATENT OFFICE

105,264

DESIGN FOR AN AUTOMOBILE SIGNAL

Charles Catalano, Elmont, N. Y.

Application May 24, 1937, Serial No. 69,532

Term of patent 7 years

To all whom it may concern:

Be it known that I, Charles Catalano, a citizen of the United States, and a resident of Elmont, in the county of Nassau, and State of New York, have invented a new, original, and ornamental Design for an Automobile Signal, of which the following is a specification, reference being had to the accompanying drawing, forming part thereof.

Figure 1 is an elevational view of an automobile signal, showing my new design.

Figure 2 is a top plan view thereof.

I claim:—

The ornamental design for an automobile signal as shown.

CHARLES CATALANO.
